FIG. 2

UNITED STATES PATENT OFFICE

2,431,780

LOAD-CARRYING MEANS

William A. Theal, Sullivan, Ind.

Application April 23, 1946, Serial No. 664,358

4 Claims. (Cl. 224—5)

1

The invention aims to provide a new and improved means for permitting two men to easily carry such heavy objects as refrigerators, stoves, large loaded crates or packing boxes, etc., the construction being such that the weight is suspended from the men's shoulders, leaving their arms and hands free to steady the load.

Figure 1 of the accompanying drawings is a side elevation showing the manner of using the invention.

Figure 2 is a perspective view.

A preferred construction has been illustrated and will be rather specifically described, but attention is invited to the possibility of making variations within the scope of the invention as claimed.

Two flexible harnesses 5 and 5a are provided to be worn by two men facing opposite sides of the load 6, two flexible sling straps 7 and 7a are connected with the harnesses 5 and 5a respectively, to extend under the load, and a flexible tie strap 8 connects the lower portions of said sling straps 7 and 7a with each other to prevent them from slipping out of place. The entire load is suspended from the men's shoulders and their arms and hands are left free to steady the load.

The harnesses 5 and 5a and their sling straps 7 and 7a, are duplicates and a specific description of one will, therefore, suffice. This description will be directed to harness 5 and its sling strap 7.

The harness 5 is in the general form of a figure 8, with the junction 9 of its two loops 10 located at the back of the harness, whereby one side of each loop 10 provides an arched shoulder strap 11 extending upwardly, forwardly and downwardly from the junction 9, and the other side of each loop 10 provides a rib strap 12 declining forwardly to the front end of said shoulder strap 11. The ends of the sling strap 7 are connected with the lower ends of the loops 10, and these loops are of such size as to extend well below the arm pits of the wearer, for comfort and to give his arms freedom of movement at the outer sides of said loops.

In the present disclosure, each loop 10 includes a side ring 13 to which the lower ends of the two straps 11 and 12 are connected, and the upper ends of said straps 11 and 12 of both loops 10, are connected to a back ring 14. The shoulder straps 11 are adjustable in length, by means of suitable buckles 15.

The ends of the sling strap 7 are provided with snap hooks 16 engaging the side rings 13, and said strap 7 is adjustable in length, by means of a suitable buckle 17.

2

The above description of the harness 5 and its sling strap 7 is readable equally well on the harness 5a and its sling strap 7a simply by adding the exponent *a* to each reference number used in said description.

The tie strap 8 is provided with loops 18 at its ends through which the lower portions of the sling straps 7 and 7a extend slidably, permitting centering of said tie strap 8 regardless of the lengths to which said sling straps 7 and 7a may be adjusted. This tie strap 8 is adjustable in length, by means of an appropriate buckle 19.

Either before or after the men apply their harnesses, the straps 7, 7a and 8 may be easily placed under the load by simply tilting the latter in required directions, and when the harnesses are applied and any required adjustments made, the load may be easily lifted and carried, and steadied by the hands. As it is only required that the load clear the ground or floor by a few inches, the initial lifting may be accomplished simply by straightening the legs from a knee-bent position at which the straps are taut, and this operation is much easier on the men than straightening up after bending from the waist.

From the foregoing, it will be seen that novel and advantageous provision has been made for attaining the desired end. Attention, however, is again invited to the possibility of making variations, and obviously I am not restricted to any material or materials. Moreover, the device may well be made of different sizes, if desired, instead of adjustable to fit men of all sizes.

I claim:

35. 1. A load carrying means comprising two sling straps to extend under the load, adjustable means connecting the lower portions of said two sling straps with each other to prevent them from slipping from under the load, and two harnesses to be worn by two men facing opposite sides of the load, the ends of one of said sling straps being connected to one of said harnesses in positions for location at opposite sides of one of the men, the ends of the other of said sling straps being connected to the other of said harnesses in positions for location at opposite sides of the other of the men, said harnesses including shoulder straps for suspending the load from the men's shoulders, leaving the arms and hands free to steady the load.

40. 2. A load carrying means comprising two sling straps to extend under the load, a tie strap connecting the lower portions of said two sling straps with each other to prevent them from slipping from under the load, and two harnesses to be

worn by two men facing opposite sides of the load, the ends of one of said sling straps being connected to one of said harnesses in positions for location at opposite sides of one of the men, the ends of the other of said sling straps being connected to the other of said harnesses in positions for location at opposite sides of the other of the men, said harnesses including shoulder straps for suspending the load from the men's shoulders, leaving the arms and hands free to steady the load.

3. A structure as specified in claim 2; each of said sling straps including means for varying its effective length; said tie strap having loops on its ends through which said lower portions of 15 said sling straps extend slidably, whereby said tie strap may be centered regardless of the effective lengths to which said sling straps may be adjusted.

4. In a load carrying means, a harness to be 20 worn by a man, said harness being in the form of a figure 8 with the junction of its two loops disposed at the rear of the harness, whereby one side of each loop may form a shoulder strap extending upwardly, forwardly and downwardly 25 from said junction, and the other side of each loop may form a rib strap declining forwardly.

5 from said junction to the lower end of said shoulder strap; a second harness to be worn by a second man facing the first mentioned man, said second harness being substantially a duplicate of the harness aforesaid; and two sling straps to extend under the load, the ends of one of said sling straps being connected with the lower ends of the loops of one of said harnesses, the ends of the other of said sling straps being connected with the lower ends of the loops of the other of said harnesses; and a tie strap connecting the lower portions of said sling straps with each other.

WILLIAM A. THEAL.
